UNITED STATES PATENT OFFICE.

ELMER E. BRADLEY, OF CLINTON, IOWA.

AIR-NOZZLE FOR TRACK-SANDERS.

1,280,146.

Specification of Letters Patent.

Patented Oct. 1, 1918.

Application filed January 8, 1918. Serial No. 210,922.

To all whom it may concern:

Be it known that I, ELMER E. BRADLEY, a citizen of the United States, residing at Clinton, in the county of Clinton and State of Iowa, have invented certain new and useful Improvements in Air-Nozzles for Track-Sanders, of which the following is a specification.

This invention relates to air nozzles for track sanders, and aims primarily to simplify and improve the construction and operation of devices of this character as well as to increase the efficiency of the same.

A further object of the invention is to provide a nozzle for use in connection with track sanders which is constructed in such manner as to obviate the possibility of the air discharge ports becoming sealed or clogged with sand or dust, thereby obviating the possibility of the sanding device being rendered inoperative.

A still further object is to provide an injector or nozzle of the character mentioned which is adaptable to practically all types of fluid pressure sanding devices now in use, which is composed of but few simple, inexpensive and easily assembled parts, which is capable of being readily detached from the sanding apparatus for the purpose of cleaning or repairing, which may be readily assembled or dismantled without the aid of special skill or tools, and which will enable the sanding apparatus to be immediately responsive upon the application of fluid pressure.

With these objects in view, together with others which will appear as the description proceeds, the invention resides in the novel formation, combination, and arrangement of parts, all as will be described more fully hereinafter, illustrated in the drawings, and particularly pointed out in the claims.

In the drawings:

Figure 1 is a longitudinal sectional view taken through a track sanding air nozzle of my invention,

Fig. 2 is a rear elevation of the improved nozzle,

Fig. 3 is an enlarged side elevation of the end of the improved nozzle, and

Fig. 4 is a sectional view taken substantially upon line 4-4 of Fig. 3.

Referring now more particularly to the drawings, 5 indicates the casing for the injector or nozzle, having reduced nipples 6 and 7 at its ends. These nipples are both

provided upon their exterior surfaces with screw threads as shown, and the bore of the nipple 7 is internally threaded.

The improved air nozzle is indicated generally at 8, and comprises an elongated shank having a relatively large central bore 9 extending throughout substantially the entire length thereof. The rear end of this nozzle is enlarged and is exteriorly threaded so as to permit of the same being screwed into the bore of the nipple 7, and a jam nut 10 is threaded upon the said rear end of the nozzle shank to hold the latter in proper adjusted position in its retaining nipple. The forward end of the nozzle is provided with a head 11, the said head being pointed at its forward end, and provides an annular rearwardly facing wall or shoulder 12 at its rear end. A relatively small port or opening 13 extends from the point of the head 11 rearwardly and communicates at its rear end with the larger bore 9 of the nipple. The head 11 is also provided with a plurality of angularly disposed ports 14, which communicate at their inner ends with the larger part of the bore 9, and extend rearwardly and open out in the rearwardly facing wall or shoulder 12 of the said head.

To enable the improved injector or nozzle to be applied to the sanding apparatus of a locomotive, an internally threaded sleeve 15 is provided, the said sleeve being provided at one end with an annular flange 16 adapted to be engaged by and firmly held in position upon the nipple 6 by a coupling nut 17. It will be understood that the threaded end of the sleeve 15 may be applied to the pipe or any other part of the sanding apparatus. It will also be observed that the bore of the sleeve 15 is reduced at its rear end, and the angularly inclined walls of the bore approaching the reduced end of the said nipple will assist in preventing sand or dust working back into the chamber of the casing 5.

In operation, the sleeve 15 is coupled to the sand box or distributing chamber of the sanding apparatus, and an air pipe may be attached to the nipple 7. Air entering the bore 9 of the nipple will escape therefrom through the forwardly extending opening 13 of the nipple as well as through the angularly and rearwardly disposed ports 14. The air will then escape from the nozzle chamber through the sleeve 15, and will force the sand of the apparatus through the distribut-

ing pipe. By arranging the nozzle 8 in the manner mentioned, it is obvious that the chamber within which the nozzle is positioned may contain a considerable amount 5 of sand or dust without in any way affecting the operation of the said nozzle. By directing the ports 14 in the nozzle rearwardly, the opportunity for clogging of the same by sand or dirt is obviated. The degree of air 10 pressure applied to the inner end of the sleeve 15 may be varied by adjusting the nozzle 8 inwardly or outwardly of the casting 5.

From the foregoing it is obvious that I 15 have provided a nozzle for track sanding devices which will perform its functions perfectly and with the least opportunity of being rendered inoperative. The various parts constituting the complete injector are 20 of simple and inexpensive construction, enabling the device to be easily taken apart and assembled, and any of the parts may be replaced at small cost.

While the present is a disclosure of the 25 preferred embodiment of the invention, it is to be understood that the invention is not limited thereto, as various changes in the minor details of construction, proportion, and arrangement of parts may be resorted 30 to if desired without departing from the spirit of the invention as defined by the appended claims.

I claim:

1. In a device of the class described, a 35 casing having an outlet only in one end thereof, a nozzle extending into said casing in alinement with said outlet, and the said nozzle having ports communicating with the bore thereof and disposed at an angle to the 40 direction of said nozzle.

2. In a device of the class described, a 45 casing having an outlet only in one end thereof, a nozzle extending into said casing

and in alinement with said outlet, a head on the end of said nozzle and the said head being provided with ports communicating with the bore of said nozzle and disposed at an angle to the direction of said nozzle. 45

3. In a device of the class described, a casing having an outlet at one end thereof, a nozzle in said casing and alined with said outlet, a head on said nozzle providing a rearwardly facing shoulder, and the said head having angularly disposed ports extending from the said shoulder to the bore 55 of said nozzle.

4. In a device of the class described, a casing having an outlet at one end thereof, a nozzle projecting into said casing and being alined with said outlet, a pointed head on said nozzle, the said head providing an angularly rearwardly facing wall, the bore of said head being reduced at its end, and the said head being provided with angularly disposed ports opening in said wall and being in communication at their inner ends with the larger port of the bore of said nozzle. 60

5. In a device of the class described, a casing, exteriorly threaded nipples at the 70 ends of said casing, threads on the interior walls of one of said nipples, an exteriorly threaded nozzle adapted to be inserted in the last named nipple, a head on the inner end of said nozzle, a nut for holding said 75 nozzle in said nipple, a coupling nut threaded on the other of said nipples, and a sleeve held by said nut and communicating with the interior of said casing.

In testimony whereof I affix my signature 80 in presence of two witnesses.

ELMER E. BRADLEY.
